RETURN BEND FITTING FOR OIL STILLS

Herbert C. Stockham, Birmingham, Ala., assignor
to Fred C. Fantz, Webster Groves, Mo.

Application February 15, 1933, Serial No. 656,799

13 Claims. (Cl. 285—20)

My invention relates to that class of return bends which are designed to be used in the cracking coils or tube banks, of a refinery, for the purpose of connecting adjacent tubes to each other so as to provide a continuous passage therethrough.

It is well known that it is a highly desirable end to provide these tubes, which frequently have to be removed, with demountable return bends so that the tubes can be replaced, removed, or inspected, without the necessity of destroying the adjacent tube.

In the standard one piece header box or return bend it is well known that it is frequently, if not invariably necessary to destroy the adjoining tube in order to remove a defective one as the headers are permanently attached to the ends of the tubes.

My construction provides for the use of upset tubes having shoulders formed on their ends, which are demountably secured to a detachable housing so that if it becomes desirable to remove or replace one of the tubes, it can be taken out without disturbing the adjacent tube. I have also provided convenient means for the removal of the return bend which connects the adjacent tubes so as to permit access to their interior for the purpose of cleaning them of the surplus coke, which deposits therein during the refining operation.

My means of accomplishing the foregoing objects may be more readily understood by having reference to the accompanying drawings, which are hereunto annexed and are a part of this specification, in which—

Fig. 1 is a vertical sectional view of my improved construction;

Fig. 2 is a top or plan view of the same, the housings and the return bend being omitted for the sake of clearness;

Fig. 3 is a vertical sectional view of a modified form of construction;

Fig. 4 shows at its left side, a top or plan view of the device shown in Fig. 3, with the housing and return bend omitted, while at the right hand half of this figure, I have shown a modified form of construction in which the bottom of the housing member is horseshoe shaped so that it may be slipped into place after the return bend is placed in assembled position.

Fig. 5 is a vertical sectional view on the line 5—5 in Fig. 1;

Fig. 6 is an end elevation of one of the housings shown in Fig. 1, a portion of the exterior

wall being broken away to show the interior construction;

Fig. 7 is a bottom view of the housing as shown in Fig. 6;

Fig. 8 is a fragmentary detail view of one of the bottom plates used in the construction illustrated in Fig. 1;

Fig. 9 is a vertical sectional view taken on the line 9—9 in Fig. 3;

Fig. 10 is an end elevation of one of the housing members, shown in Fig. 3, a portion of the wall being broken away to show the interior construction;

Fig. 11 is a side elevation of one of the bottom plates shown in Fig. 4; a portion of one of the two halves being broken away for the sake of clearness;

Fig. 12 is a side elevation of a modified form of construction, a portion of the exterior being broken away and showing one-half of the structure in section; and

Fig. 13 is a top or plan view of the modified form of Fig. 12, a portion of one of the housings being broken away to show the means of locking the housing sections against disengagement with the bottom plate.

Fig. 14 is a vertical sectional view of a modified form of construction shown at the right hand half of Fig. 4;

Fig. 15 is a top or plan view of the same, part 30 of the housing and the return bend being omitted for the sake of clearness;

Fig. 16 is a vertical sectional view of a modified form of construction;

Fig. 17 is a side elevation of the plates partly 35 broken away to show the interior of one of the halves of the plates.

Similar reference numerals refer to similar parts throughout the entire description.

As shown in the drawings, a conventional return bend 1 is provided to connect a pair of adjacent still tubes 2 and 3 so as to provide a continuous passage therethrough. These tubes 2 and 3 are provided with upset or shouldered portions 4 and 5 adjacent their end. The shoulders 4 on these tubes are engaged by a pair of plates 6 and 7, these plates having tube surrounding portions 8, which engage the shoulders 4 and 5 on the tubes 2 and 3.

Each of the plates adjacent to the tube surrounding portions is provided with upwardly extending semi-cylindrical portions 10 and 11. As shown in Fig. 2 the upwardly extending portions 10 and 11 are provided with outwardly extending circumferential flanges which are provided with 55

a plurality of slots 12 which form a number of spaced lugs 13.

The plates are fitted around the tubes 2 and 3, and a channel 14, the walls of which form a saddle for the central web 15 which forms the connecting portion of the plates.

A bolt 16 is then screwed into the channel, drawing it tightly up against the sides of the plates so that they are held securely locked against the shoulders on the tubes.

I provide a pair of housing sections which are separate and are each formed with substantially annular portions 17, each of which is provided with a pair of upwardly extending side walls 18 and 19. These walls may be joined together at the top, forming hubs 20, in which are mounted set screws 21, as clearly seen in Figs. 5 and 6. These hubs may be hexagonal for the reception of a wrench if desired. The inner end of the set screws 21 engage abutments 22 formed on the external wall of the return bend 1.

In some cases it may be found desirable to form the upwardly extending side walls 18 and 19 without bringing them together and joining them in one piece at the top, in which case any one of the well known types of toggles such as shown in Figs. 14 and 15 may be employed for the purpose of holding the set screws 21.

The inner wall of each of the annular portions 17 of the housing is provided with a recessed circumferential groove which is provided with spaced lugs 23, which are adapted to fit the spaces 12 between the spaced lugs 13 on the upwardly extending semi-cylindrical portions 10 and 11 formed on the plates 6 and 7.

It may, in some cases, be found desirable to construct the housing member as shown at the right hand half of Fig. 4. In this construction instead of providing an annular portion 17, the lower part of the housing is horseshoe shaped, as clearly seen in this half of Fig. 4 so that it may be slipped under the circumferential flanges formed on the upwardly extending semi-cylindrical portions 10 and 11 on the plates 6 and 7, where this is done obviously the slots 12 may be omitted. It may, in some cases, be found desirable to provide for locking the housing by rotating it—say one-sixteenth of a turn this can be done after the return bend is in place.

The device is assembled in the following manner: The plates are fitted to the tubes 2 and 3 and the channel 14 is bolted in place, thus securely locking the web 15 and the tube engaging portions 8 of the plates with the shoulders 4 and 5 on the tubes 2 and 3. The lugs 23 on the annular member 17 of the housing members are then fitted into the spaces 12 between the lugs 13 on the upwardly extending semi-cylindrical portions 10 and 11 and the housing is given a slight turn sufficient to cause the spaced lugs 23 to be beneath the spaced lugs 13 on the plates, when by tightening the set screws 21 it will be apparent that the return bends will be drawn into a leak-proof joint at the end of the tubes.

In this construction when the return bend 1 is to be removed, the housing sections are removed with it, being turned a sufficient portion of a revolution so as to bring the lugs 23 in register with corresponding spaces 12 between the lugs 13, when the whole assembly can be easily removed from its assembled positions. When toggles are employed then it is not necessary to remove the housing members. Means for locking the housing sections against disengagement is shown in Figs. 12 and 13 in which an arcuate

key 26 is provided which is fitted to one of the spaces 12 between the lugs 13. Obviously, when this key is inserted, the housing cannot be rotated to remove it. Although I have shown a specific type of means for locking the housing in place it will be clear to persons skilled in the art that any suitable or desired means may be employed for this purpose.

In the modified form of construction as shown in Figs. 3, 4, 10 and 11, the external walls 27 of the semi-cylindrical portions 10 and 11 on the plates 6 and 7 are provided with threads 28 and corresponding internal threads 30 are cut in the annular portions 17 of the housing members. The housing members may then be screwed on to the upwardly extending portions of the plates and remain permanently in such position, except when it is necessary or desirable to remove or replace the tubes. A conventional form of securing means is shown for this modified form which comprises toggles or plates 24 which engage a slot 35 formed in the upwardly extending side walls 18 and 19 of the housing members. The set screws 21 are mounted in the plates 24. The operation of completing a tight joint is identical with that of the previously described form of this device.

Although I have shown a specific type of joint between the return bend of the tube it will be apparent to persons skilled in the art that no special type of joint is necessary for the proper functioning of my invention and I do not intend or desire to be limited to any specific type of joint for this purpose or to any specific type of toggle for holding the set screws 21. Neither do I desire to be limited to the specific type of saddle or channel arrangement for holding the plates together as numerous changes may be made, all of which will be within the scope of the herein-after contained claims.

In fact, in some instances, it may be found desirable to entirely dispense with the saddle or any securing means for holding the plates 6 and 7 together. It may also be deemed desirable in some cases to have the annular portion 17 of the housing discontinuous, which obviously can be done without departing from the spirit of my invention.

Having described my invention what I regard as new and desire to secure by Letters Patent is:

1. In a refinery apparatus, a conventional return bend adapted to connect adjacent tubes in a still, comprising a compound housing consisting of two sections, each of which has an annular member with upwardly extending side walls, there being slots in said side walls and toggles mounted therein, set screws in said toggles, the inner ends of which engage said return bend, a pair of plates having tube surrounding portions which engage the shoulders on said tubes, upwardly extending semi-cylindrical portions on said plates, shoulders on the external walls of said portions, adapted to engage registering means on said annular portions and means to lock said plates together.

2. In a refinery apparatus, a conventional return bend adapted to connect adjacent tubes in a still, comprising a compound housing consisting of two sections, each of which has an annular member with upwardly extending side walls, there being slots in said side walls and toggles mounted therein, set screws in said toggles, the inner ends of which engage said return bend, a pair of plates having tube surrounding portions which engage the shoulders on said tubes,

upwardly extending semi-cylindrical portions on said plates, a circumferential flange on said portion, spaced lugs on said flange, adapted to engage inwardly extending spaced lugs on the annular members, and means to lock said plates together.

3. In a refinery apparatus, a conventional return bend adapted to connect adjacent shouldered tubes in a still, comprising a compound housing consisting of two sections, each of which has an annular member with upwardly extending side walls, there being slots in said side walls and toggles mounted therein, set screws in said toggles, the inner ends of which engage said return bend, a pair of plates having tube surrounding portions which engage the shoulders on said tubes, upwardly extending semi-cylindrical portions on said plates, threads on said semi-cylindrical portions adapted to engage threads on said annular members, and means to lock said plates together.

4. In a refinery apparatus, a conventional return bend adapted to connect adjacent tubes in a still, comprising a compound housing consisting of two sections, each of which has an annular member with upwardly extending side walls, there being slots in said side walls and toggles mounted therein, set screws in said toggles, the inner ends of which engage said return bend, a pair of plates having tube surrounding portions which engage the shoulders on said tubes, upwardly extending semi-cylindrical portions on said plates, shoulders on the external walls of said portions, adapted to engage registering means on said annular portions, means to lock said plates together, said means comprising a channel in which said plates rest and a bolt which passes through said plates and channel to lock the plates securely together.

5. In a refinery apparatus, a conventional return bend adapted to connect adjacent tubes in a still, comprising a compound housing consisting of two sections, each of which has an annular member with upwardly extending side walls which are joined at the top and form a hub, set screws in said hub, the inner ends of which engage said return bend, a pair of plates having tube surrounding portions which engage the shoulders on said tubes, upwardly extending semi-cylindrical portions on said plates, shoulders on the external walls of said portions, adapted to engage registering means on said annular portions and means to lock said plates together.

6. In a refinery apparatus, a conventional return bend adapted to connect adjacent tubes in a still, comprising a compound housing consisting of two sections, each of which has an annular member with upwardly extending side walls, there being slots in said side walls and toggles mounted therein, set screws in said toggles, the inner ends of which engage said return bend, a pair of plates having tube surrounding portions which engage the shoulders on said tubes, upwardly extending semi-cylindrical portions on said plates, interengaging means on said housing sections and said semi-cylindrical portions to lock said parts together, and means to lock said plates together.

7. In a refinery apparatus, a conventional return bend adapted to connect adjacent tubes in a still, comprising a compound housing consisting of two sections, each of which has an annular member with upwardly extending side walls, there being slots in said side walls and toggles mounted therein, set screws in said toggles, the inner ends of which engage said return bend, a

pair of plates having tube surrounding portions which engage the shoulders on said tubes, upwardly extending semi-cylindrical portions on said plates, shoulders on the external walls of said portions, adapted to engage registering means on said annular portions.

8. In a refinery apparatus, a conventional return bend adapted to connect adjacent tubes in a still, comprising a compound housing consisting of two sections, each of which has an annular member with upwardly extending side walls, there being slots in said side walls and toggles mounted therein, set screws in said toggles, the inner ends of which engage said return bend, a pair of plates having tube surrounding portions which engage the shoulders on said tubes, upwardly extending semi-cylindrical portions on said plates, a circumferential flange on said portion, spaced lugs on said flange, adapted to engage inwardly extending spaced lugs on the annular members.

9. In a refinery apparatus, a conventional return bend adapted to connect adjacent tubes in a still, comprising a compound housing consisting of two sections, each of which has an annular member with upwardly extending side walls, there being slots in said side walls and toggles mounted therein, set screws in said toggles, the inner ends of which engage said return bend, a pair of plates having tube surrounding portions which engage the shoulders on said tubes, upwardly extending semi-cylindrical portions on said plates, threads on said semi-cylindrical portions adapted to engage threads on said annular members a saddle which straddles said plates between said tubes and means to draw said saddle tightly against the sides of said plate.

10. In a refinery apparatus, a conventional return bend adapted to connect adjacent tubes in a still, comprising a compound housing consisting of two sections, each of which has an annular member with upwardly extending side walls, there being slots in said side walls and toggles mounted therein, set screws in said toggles, the inner ends of which engage said return bend, a pair of plates having tube surrounding portions which engage the shoulders on said tubes, upwardly extending semi-cylindrical portions on said plates, interengaging means on said housing sections and said semi-cylindrical portions to lock said parts together the outer walls of said plates between the tubes being inclined, a saddle formed of a channel, the sides of which are fitted to the inclined walls of said plate, located between said tubes, and means to draw said saddle tightly against the sides of said plate whereby the plates are locked together.

11. In a refinery apparatus, a conventional return bend adapted to connect adjacent tubes in a still, comprising a compound housing consisting of two sections, each of which has a horseshoe shaped member with upwardly extending side walls, there being slots in said side walls and toggles mounted therein, set screws in said toggles, the inner ends of which engage said return bend, a pair of plates having tube surrounding portions which engage the shoulders on said tubes, upwardly extending semi-cylindrical portions on said plates, interengaging means on said housing sections and said semi-cylindrical portions to lock said parts together.

12. A conventional return bend for refinery apparatus, adapted to connect adjacent tubes of a still to provide a continuous passageway there-through, a pair of shouldered tubes, a compound

housing comprising annular members having upwardly extending side walls thereon, a pair of plates, there being mating semi-circular openings therein, adjacent their ends, mating upwardly extending semi-cylindrical portions on said plate adapted to interlock with said annular members and to be locked on said tubes, a saddle adapted to straddle the central portion of said plate, means to draw said saddle tightly against said plate, and means to draw the return bend on said tubes into a leak proof joint.

13. A conventional return bend for refinery apparatus, adapted to connect adjacent tubes of a still to provide a continuous passageway there-through, a pair of shouldered tubes, a compound

housing comprising annular members having upwardly extending side walls thereon, a pair of plates, there being mating semi-circular openings therein, adjacent their ends, mating upwardly extending semi-cylindrical portions on said plate adapted to interlock said annular members and to be locked on said tubes, a saddle formed of a channel, the sides of which are fitted to the sides of said plate, a bolt which extends through said plate and into said saddle whereby the tightening of said bolt will lock the said plates tightly against the shoulders on the tubes and means to draw the return bend and said tubes into a leak proof joint.

HERBERT C. STOCKHAM. 15
